[57] CLAIM

The ornamental design for a vented floor-model roach trap, as shown and described.

DESCRIPTION

FIG. 1 is a side view of the vented floor-model roach trap showing the visible interior also that is viewable through the transparent dome-shaped walls having vent slits therein.

FIG. 2 is a top view of the trap shown in FIG. 1, showing also the conical opening in the central top portion. FIG. 3 is a bottom view of the trap shown in FIGS. 1 and 2, showing the bottom of the base thereof.

FIG. 1

FIG. 2

FIG. 3
